MEANS FOR LIFTING LIQUIDS

Alexander Boynton, San Antonio, Tex.

Application May 3, 1934, Serial No. 723,665

11 Claims. (Cl. 103—234)

My invention relates to a means for lifting liquids from wells and propelling liquids through pipe lines by the propulsive force of compressed air or gas expanding under or behind a slug of liquid intermittently admitted into the eduction tube of a well or into a pipe line.

The slug of liquid is admitted into the eduction tube of a well or into a pipe line by means of a valve that controls the admission of liquid there-
10 to (hereinafter referred to as the liquid intake valve) after one of two valves that control the admission of compressed air or gas thereto (hereinafter referred to as the air or gas valves) moves from one seat, referred to as the first seat, and
15 the other air or gas valve closes upon another seat, referred to as the second seat; one of the air or gas valves and the liquid intake valve being urged to the only position in which they are both closed by a spring which may work in
20 conjunction with a latching means tending to hold one of the air or gas valves and the liquid intake valve closed in the first position, and the other of the air or gas valves closed while the liquid intake valve is open in the second position.
25 The force of the air or gas is utilized to hold one of the air or gas valves seated upon the second seat while the slug of liquid to be expelled is entering the eduction tube or pipe line through the liquid intake valve. The weight or
30 back pressure of the slug of liquid thus admitted into the eduction tube or pipe line is utilized to unseat one of the air or gas valves after it has closed upon the second seat, and to hold both of the air or gas valves open intermediate their two
35 seats, while in that position the liquid intake valve cuts off the admission of more liquid until the slug has been expelled; whereupon one of the air or gas valves again assumes the closed position upon the second seat with the liquid intake valve open. This cycle is automatically
40 repeated during the period of operation.

An important object of this invention is to provide means whereby slugs of different weights or lengths may be expelled from wells by means
45 of simply varying the pressure of the air or gas used to lift the slug. By increasing the air or gas pressure the length or weight of the slug is increased or vice versa; thereby overcoming the serious difficulty of having to remove the device from the well to change the adjustment so as to cause it to expel slugs of different lengths or
50 weights.

These objects are attained by mechanisms illustrated in the accompanying drawings in
55 which:

Fig. 1 is a vertical section of a well equipped with this device, using pressure tubing.

Fig. 2 is a vertical section of a portion of the device and a portion of the pressure tubing within which the device is installed.

Fig. 3 is a vertical section of a lower portion of the device shown in Fig. 2.

balls and housing members on the line 23—23, Fig. 7.

Fig. 24 is a side view of the air or gas valves, latching shaft, and liquid intake valve shown in Fig. 2.

The same numerals are employed to indicate and refer to the same parts throughout the several views in all forms of the invention.

I have shown the well as being equipped with 10 an outer casing 1 having above the ground surface a casing head 4 thereon, said casing head being provided with lateral outlets, one of which is closed by the bull plug 22, the other being connected with a pipe 70 for air or gas. The upper 15 end of the casing head is sealed about an inner pressure tube 2 by any preferred means and I have shown a radial plate 6 on the pressure tube fitting within a casing head and held in position by a cap 5 screwed over the upper end of the 20 casing head. The engagement not only forms a seal but holds the inner pressure tube rigidly in position.

The pressure tube 2 extends above the casing head and is connected by means of a coupling 7 25 with a T 8 having a lateral branch 8^a connected to the air or gas line 23. The upper end of the T is formed to support the inner flow pipe 3, which is closed about by the cap 9, which is clamped against the packing 11, thus making a 30 seal at that point.

The pressure tube proximate its upper end has a nipple 2^a. Said tube is connected at its lower end to a swaged coupling 13, which has a lower tapered seat 13^a to be engaged by the lead seal 35 12^a on the flow tube. The lower end of the coupling 13 is connected to a tubular housing 16 connected at its lower end to the coupling 18.

Within the housing 16 is a valve 14 held resiliently upwardly by a spring 15 to engage normally within a seat 13^b at the lower end of the swaged coupling 13. Said spring 15 rests upon an annular plate 17 in the coupling 18. Below the valve 14 the tubing may be extended downwardly as far as is desired and I have shown the 45 same as connected through a nipple 21 to a perforated pipe 19 having openings 19^a therein and closed at its lower end by a cap 20.

The tubing may be extended to rest on bottom of the well as shown in Fig. 1, or it may be 50 allowed to hang from the casing head with its lower end anywhere above the bottom of the well.

While the pressure tubing is being lowered into the well, seal valve 14 contacts seat 13^b upon 55 which it is held by the force of seal valve spring 15 which spring is held in position within housing nipple 16 by plate 17 threaded secured within coupling 18. When the flow tubing is lowered into position shown in Fig. 1, the slotted extension 12 forces the seal valve down to the position shown in Fig. 1 whereupon well liquid can enter the device via slots 12^a, the well liquid entering the pressure tubing extension through ports 19^a of intake nipple 19, passing through 60 seal valve spring 15, and bypassing the seal valve 14 between fins 14^a. A cap 20 may support all or part, preferably part, of the tubing weight upon the bottom of the well or nipple 21 and all lower parts of the pressure tubing extension may 65 be omitted, in which case the well liquid will, of course, enter the pressure tubing extension through the lower end of coupling 18.

The device shown in Fig. 2 being installed as 70 shown in Fig. 1, compressed air or gas is supplied into the pressure tubing from pipe line 23

(if the well does not produce enough gas to flow it). This air or gas in the pressure tubing can enter the flow tubing only through ports 24^a of the air or gas intake connection member 24 via passage 24^b, chamber 24^c, around air or gas 5 valves 25 and 26, through upper slots 27^a, and upward into flow tubing 3 via the cored passages 24^d through the air or gas intake connection member 24.

Air and gas valves 25 and 26 are interposed in 10 the path of the air or gas flow from the pressure tubing into the flow tubing. The valve shank 26^a is threadedly connected to latching shaft 29 formed at its lower end into the liquid intake valve 29^a. The valve 25 is normally held upon 15 its seat 24^d by the force of air or gas valve spring 28 contacting with an upper spring shoe 30 at its upper end and contacting with a lower spring shoe 31 at its lower end. A felt washer 32 is interposed between the spring shoe 31 and the 20 ball roof 33, both latter members being of circular wedge shape, as shown, to force the felt washer into engagement with the latching shaft 29 and the spring housing nipple 27 in order to keep sand or other solid substances in the well 25 liquid from fouling the latch balls 34. Said balls rest upon the ball floor 35 threadedly positioned in nipple 27, and locked in position by plug 36, both ball roof and ball floor being beveled as shown to urge the latch balls into engagement 30 with the latching shaft.

Lower slots 27^b in the housing nipple 27 are to allow free circulation of liquid through and around the spring 28 to prevent solids from settling and interfering with the latching assembly. 35

Liquid intake valve 29^a fits within a central bore through valve sleeve plug 37 and seal ring retaining member 38. Seal ring 39 is clamped in place by said retaining member and may be of oil proofed rubber or any other durable resilient 40 material shown somewhat enlarged in Fig. 19. It is housed as shown and held in leak proof engagement with the valve 29^a by the pressure of well liquid acting upon its outer cupped surface, finding access thereto through vertical passages 45 38^a and recess 38^b. A locking ring 40 and packing 41 secure the valve sleeve plug 37 in position and prevent the leakage of well liquid along the threads around these members.

The valve seat member 42 for the valve 26 is 50 pressed in against the shoulder 24^e and securely locked in place by the nipple 27. The case nipple 43 is threadedly connected at its upper end to the air or gas intake connection member 24 and at its lower end it is threadedly connected 55 to the lead seal carrier nipple 12.

Inside of the nipple 12 previously noted, is secured a check valve housing 44 within which is a check valve 45 seated upon a yieldable member 46 resiliently held against the base of the 60 check valve housing 44 by check valve spring 47, the lower end of which rests upon the check valve seat member 48 the base of which is threadedly connected into nipple 12 and holds the liquid intake governor 49 locked in position upon 65 shoulder 12^b.

A latching means similar to the one shown in Figs. 2, 7, and 8, but not identical therewith, is shown in my copending patent applications Serial Numbers 638,858; 637,710; 638,859; and 70 646,389; the first three of which have now evenuated into Patents 1,968,633, 2,010,135, and 2,006,909, respectively.

While the well is standing, that is without sufficient air or gas pressure in the pressure tubing 75

to unseat valve 25, the valve will remain closed upon seat 24^d and the liquid intake valve will remain closed as shown in Fig. 2. When air or gas of sufficient value to operate the device is placed within the pressure tubing, valve 25 is forced from its seat and valve 26 seats with a slam on seat 42^a. This movement lowers the liquid intake valve 29^a to a point where the upper end of the enlarged portion is slightly below the port in which it fits in the closed position shown in Fig. 2. This valve in the open position is shown in Figs. 15 and 16 in which figures the valves are identical with this valve except for the lower ends thereof. Well liquid now enters the flow tubing 3 through the case nipple 43 and the cored passages 24^f. When enough well liquid has entered the flow tubing to exert sufficient back pressure on the lower end of the valve 26 it unseats and recedes to a position where valves 25 and 26 are intermediate their respective seats. It stays in this position until the slug of liquid is expelled from the flow tubing. After the valve 26 has been unseated by pressure of well liquid both valves will remain intermediate their respective seats until the slug is expelled, because valve 26 can not again seat until the pressure that unseated it is reduced. This cannot happen while the slug remains in the flow tubing. Neither can the valve 25 seat during the same time because the back pressure from the slug plus the force of spring 28 is less than the air or gas pressure under valve 25. This is true because the back pressure from the slug plus the spring force were approximately equal when valve 26 first unseated, but when this valve recedes, spring 28 loses some of its force through expansion resulting in an out-of-balance relation between the forces tending to seat each valve, neither force being sufficient to seat either valve. When the slug is expelled from the flow tubing valve 26 again seats and another slug of well liquid enters the flow tubing and is expelled in the same manner, and so the cycle is automatically repeated. If the well liquid should be inadequate to produce the slugs often enough to cause the device to operate at maximum speed, the valve 26 will remain seated in the meantime; thus allowing no air or gas to escape or waste, and wait, so to speak, on the well to produce the slug. The surface of the well liquid shown at b—b, Fig. 1, must be high enough to force the slug into the blow tubing before the device can operate. If the well liquid rises above that level the operation is quickened. The latch causes the valve action to be snappy in both directions, or in one direction only, or the latching means may be wholly omitted. To cause the valve to move downward with a snap shoulder 29^b, Fig. 24, is caused to engage the latch balls 34 as shown. This action conserves air or gas in starting the flowing operation. To cause the valves to move upwardly with a snap the latch balls are engaged with shoulder 29^c in the lowermost position of the valves. This action hastens the closing of the liquid intake valve. The difference between the weight of the slug and the value of the air or gas pressure used to expel the slug is always equal to the total force required to compress the spring 29 far enough to allow valve 26 to seat plus whatever force the latch employs in the lowermost position of the valves. The weight of the slug may, therefore, be increased by increasing the air or gas pressure and vice versa. The higher the air or gas pressure the less will be the ratio between the

weight of the slug and the value of the air or gas pressure and vice versa.

The purpose of the check valve 45, see Fig. 3, is to prevent air or gas pressure from the pressure tubing from contacting the producing horizons of the well when the liquid intake valve is open. The check valve is held resiliently over its lower seat in member 48 in order that the liquid intake valve in its downward stroke may not be resisted by the well liquid. The travel of the check valve between its two seats is such as will allow for the displacement of the liquid intake valve in its downward stroke.

The liquid intake governor 49, an enlarged view being shown in Fig. 12, admits the well liquid through the arcuate slots 49^a, formed between ribs 49^b, in such restricted quantity that will not allow the sand or other abrasive substances often found in well liquids to unduly cut the liquid intake valve and other parts exposed to the well liquid.

The Fig. 7 embodiment differs from that shown in Fig. 2 in the means for lubricating the latching device, also it has a somewhat different air or gas valve, and a modified form of liquid intake valve. In Fig. 7 (and Fig. 8) the case nipples 43' and 43'' form the upper and lower connecting means respectively between flow tubing 3 and lead seal carrier nipple 12, respectively, as does the case nipple 43 in Fig. 2. The reducing nipple 50 is used as a fitting to threadedly connect the flow tubing to the nipple 43'. Air or gas intake connection member 24' is threadedly connected between case nipples 43' and 43'', the lower end of nipple 43'' being threadedly connected to the lead seal carrier nipple 12. The cored passages 24^d through the connection member 24' correspond to the similar passages 24^f in Fig. 2. An upward extension 24'c on the member is externally threaded to receive the lower end of a nipple 51 closed at its upper end by plug 52.

A further upward extension 24'c on the connecting member is of reduced diameter and is externally threaded to receive the lower end 45 of tube 53 the top end of which is open and stops somewhat short of contacting plug 52. Upon the upper end of this extension 24'c a ball floor 35' rests with latch balls 34 held between this member and the ball roof member 33' by a spring 28. Upon the top of said spring a spring shoe 39' fits, and contacts latch adjusting nut 54 which is locked in position by lock nut 55. More or less compression is thus had on spring 28 to adjust the latch by means of these nuts. 55

Tube 53 is filled with oil or other lubricant. On the down stroke of the valves the lubricating liquid is forced into the opening in the top end of the tube 53 above the nut 55. It will be noted that ample clearance is provided between 60 said parts and the wall of the tube 53 to allow free passage of the lubricant. On the upstroke of the valves the lubricating liquid takes the reverse path to the one just described.

The lower end of the latching chamber is 65 sealed by a plug 56 below which is a felt or other similar type washer 57 held in the position shown by a shoe 58, urged upwardly by spring 59. The lubricating liquid is, therefore, free to circulate through and around the moving parts of the 70 latching assembly and is securely contained fully isolated from impurities of the well liquid; thus to provide efficient and long lasting lubrication for the latch assembly. The same means of lubrication may, of course, be used for the spring 75

if the latch be omitted. Ports 24'b allow for air or gas communication into the upper end of tube 53 thereby to provide that the displacement of the latching shaft 60 will not pull a partial 5 vacuum on its down stroke or build up compression in its upstroke. Clearance around sub 63 above ports 24'a allows access of air or gas to ports 24'b through spring 59.

The air or gas valves 61 and 62 are threadedly 10 connected to latching shaft 60 by sub 63 above and to liquid intake valve 64 below. The air or gas valve 61 has a metal to metal sliding fit as shown but does not seat upon the lower extension of member 24' as in Fig. 2. Valve 62 seats 15 in its second position upon seat 64a of air or gas valve seat sleeve 65 secured to and depending downwardly from the member 24'. The air or gas valves function in the same manner as was described for the similar valves 25 and 26 in 20 Fig. 2.

A deflector 66 secured on valve rod 64, is formed with a cupped upper end the margin of which forms a valve seat on its upper side which engages valve 65b to supplement the sleeve valve 25 61 in securing a tight seal off in the first or upper position. Deflector 66 serves the further purpose of deflecting the air or gas upwardly during the flowing operation.

The liquid intake valve on rod 64 fits in a 30 central passage through the valve sleeve plug 67, the sleeve being locked in position by locking ring 40 with packing 41 interposed as in Fig. 2. The open position of this valve is shown in Fig. 15. The liquid intake valve is fitted on its lower 35 end with yieldable member 68 secured in place by screw 69, the purpose of this yieldable member being to form a seal in the passage when it is positioned as shown in Fig. 7, the seal being obtained by the pressure of well liquid forcing 40 the yieldable member upward and outward as is obvious, thereby providing means to secure a seal off even if the metallic portion of the valve above should wear or the sleeve be cut by abrasive substances in the well liquid.

Fig. 8 shows a further modified form of air or gas valve, different lubricating means for the latch, and different liquid intake valve from the corresponding parts employed in Figs. 2 and 7.

Nipple 51 in this embodiment is threadedly 50 connected upon the upper extension 24'a of member 24" similar in purpose to member 24 of Fig. 2 and member 24' of Fig. 7, the upper end of nipple 51 being closed by plug 71. Latching shaft 72 has a shoulder 72a firmly locked against 55 the under side of the plug 71 by means of a lock nut 73 threaded upon the upper end of the shaft 72 which projects through plug 71. Said shaft extends downward to near the lower end of the chamber in nipple 71. A nut 74 on the lower 60 end of the shaft 72 supports a spring 28 upon the top end of which ball floor 35' is resiliently held in contact with latch balls 34 which contact ball roof 33' held spaced from above by spacer tube 75 which in turn rests upon the bottom of 65 plug 76 which closes the top end of nipple 71 which is housed within nipple 51, the bottom end of nipple 71 being closed by plug 78 which is threadedly connected to sub 63' and locked by nut 79. Sub 63' is a valve rod threadedly connected at its lower end into air or gas valves 80 and 81 interior of which the liquid intake 70 valve shank locks upon the lower end of sub 63' thus to form a rigid connection between the parts.

The chamber interior of nipple 71 is filled with

lubricating liquid for the latching assembly in which chamber the lubricant is securely housed apart from the well liquid, there being no outward communication into this chamber except through the slight clearance between the upper 5 enlarged portion of shaft 72 and the central bore through plug 76 while the liquid intake valve is closed as shown. This being the normal position of these parts it will be noted that the lubrication chamber can be filled in the shop or factory 10 and the lubricant will not leak out even tho the device is inverted. The reduced section of shaft 72 extending upward to proximate the center of plug 76 provides that, in operation, the lubrication chamber can breathe on the down 15 stroke of the valves, thus preventing compression in the chamber on the down stroke and likewise preventing pulling a partial vacuum in the lubrication chamber on the upstroke of the valves. In accomplishing this purpose clearance 20 around sub 63' above ports 24'a allows free access of air or gas to the chamber in housing 51. Spacer tube 75 is slotted at its lower end as shown at 75a to provide for free circulation of lubricating liquid in the chamber. The length 25 of this spacer tube is such as will allow for an ample reservoir for lubricant above the latch balls.

Cored passages 24'd through member 24" serve the same purpose as the similar passages 30 shown in Figs. 2 and 7.

The air or gas valves 80 and 81 serve the same purpose and act the same as the similar valves 25 and 26 in Fig. 2 and valves 61 and 62 in Fig. 7.

It will be observed in Fig. 8 that the deflector 35 66' does not seat as in Fig. 7, its sole purpose in this construction being to change the direction of the air or gas with a minimum loss of energy.

The liquid intake valve, which is shown closed in Fig. 8 and open in Fig. 16, has substantially 40 the same elastic member 83 as that shown in Figs. 7 and 15 and the same screw 69 with the addition of cupped cap 84 which is slipped over the unthreaded shank of screw 69 upon which it may 45 side as the resilient member 83 changes form 50 slightly in its different positions. Pressure of well liquid exerted below will press upon cap 84 and cause member 83 to form a seal in the closed position even tho the passage in which it fits be somewhat worn or abraded.

Fig. 10 shows a modified form of liquid intake valve which may be installed in either of the embodiments shown in Fig. 7 or 8 by cutting off the liquid intake valve at c—c in either of said figures and screwing the upper threads of valve member 85, Fig. 10, upon either of said shanks above c—c. In Fig. 10 85a is a central passage, 85b the liquid intake port, 85c the liquid discharge port, and 85d designates the central bore in the lower end for the spring 86, the lower end of said valve 60 member being internally threaded to receive plug 87, detailed in Fig. 22, this plug being centrally bored to allow free passage of the shank of the member 88 which constitutes a post upon the threaded lower end of which valve 89 is thread- 65 edly connected and locked in place by lock nut 90. The other parts shown in Fig. 10 are identical with the same parts shown in Figs. 7 and 8.

It will be noted that in the closed position of the valve shown in Fig. 10 there is a slight clearance between the lower end of members 85 and 87 above valve 89 when the valve is seated as shown. This clearance is for the obvious purpose of allowing valve 89 to seat around the lower extremity of the bore through which valve mem- 75

ber 85 moves. On the down stroke of the liquid intake valve assembly, valve 89 is forced downward by the lower end of valve members 85 and 87 until port 85^b is somewhat below valve sleeve 5 plug 67 at which time well liquid enters the device through ports 85^b, vertical bore 85^a, and discharge port 85^c. This construction prevents wear of the valves by directing the path of the well liquid interior of valve member 85 instead of against the 10 valve surfaces as in Figs. 2, 7, and 8.

To illustrate how the pressure tube may be dispensed with, Fig. 17 shows that either of the devices shown in Figs. 2, 7, or 8 may be installed with a packer or lead seal, a packer being indicated at 91—92—93 resting upon liner 94, the installation being substantially the same as shown for another similar device disclosed in my co-pending applications Serial Numbers 646,389, and 721,669, filed July 9, 1932, and April 21, 1934, 15 respectively.

In Fig. 17 the casing 1 takes the place of the pressure tubing in Fig. 1. The flow tubing 3, shown slightly expanded, connects with the device as in Figs. 1, 2, 7, and 8. Reducing nipple 50, interposed as a connection member in Figs. 7 and 25 8, is eliminated in this form. The air or gas coming from an external source through connection 10 enters the device through ports 24^a and acts in all respects the same as in the other forms of the 30 invention. The upper seal between the well casing and the flow tubing is formed in the obvious manner shown and the lower seal between these members is formed by the packer.

If the well produces a large volume of gas and 35 it is desired to use part of the gas to flow the well and dispose of the surplus gas through a pipe line, a tubular connection may be made between one of the casing head side ports and the tubular extension 8^a of the Fig. 1 embodiment, thus to allow 40 the formation gas of the well to enter the pressure tubing 2, Figs. 1, 7, and 8. The surplus gas may be conveyed through a pressure relief valve not shown, into a pipe line. The pressure relief valve is old in the art and may be set to hold enough 45 pressure in the well to accomplish the flowing purpose.

If the well produces enough gas to flow it with 50 no appreciable surplus, both side outlets of the casing head and extension 8^a, Fig. 1, may be 55 plugged and formation gas admitted into the pressure tubing through perforations in the pressure tubing proximate the casing head.

The surface connections specified in the last 55 two paragraphs are clearly illustrated in my co-pending applications Serial Numbers 646,389, and 721,669, filed July 9, 1932 and April 21, 1934, respectively.

Fig. 20 shows a somewhat enlarged vertical section through the bushing member 95 used to connect air or gas intake member 24 with the swaged housing and packer supporting nipple 96. The upper internal threads connect to intake member 24. The lower internal threads connect to case nipple 43, Fig. 2, or to 43' Fig. 7, or to 43' Fig. 8. The lower external threads connect to the upper end of the housing and packer nipple 96 as is apparent in Fig. 17.

The lead seal carrier nipple 12 in Fig. 1 has its 70 lower portion cut off in the Fig. 17 embodiment and the bottom member 82 of the device proper is substituted therefor as appears in Fig. 17, this part and contents being detailed in Fig. 21, the parts in this structure being practically identical 75 with those described in connection with Fig. 3.

It is to be noted that in all of the modifications of my invention herein disclosed the air and gas valve is normally closed and when the liquid inlet opens the valve is moved to another closed position, so that during the inlet of the liquid to the 5 eduction tube no air or gas from the pressure tubing can enter the eduction tube. The air or gas is only allowed to enter after a sufficient head of liquid has accumulated in the eduction tube to create a back pressure against the control valve 10 and move it to an intermediate position between the two seats of the valve.

This arrangement of the valve makes it possible to handle slugs of liquid of different weight without adjustment of the apparatus. It will be 15 possible by the proper submergence of the device to arrange the apparatus to operate in the manner desired and I have shown in Fig. 1 a fluid level 20 b—b which illustrates the usual operation of the device.

What I claim as new is:

1. In a fluid lift device, a pressure tube, a downwardly tapered seat nipple at the lower end thereof, a flow tube, a valve housing therein, means on said housing having a sealing engagement in said seat, a gaseous fluid inlet passage from said pressure tube to said housing, upper and lower valve seats in said passage, a control valve in said passage adapted to be moved between said seats, a stem on said valve, an extension sub on said stem, 30 a liquid inlet to said housing, a liquid inlet valve on said sub slidably engaging in said inlet, said control valve being movable from one valve seat to another of said seats by pressure of the gaseous lift fluid to open said liquid inlet valve, said 35 liquid valve being again closed, and said control valve being moved to open position in response to pressure in said housing of the liquid being pumped.

2. In a fluid lift device, a pressure tube, a downwardly tapered seat nipple at the lower end thereof, a flow tube, a valve housing therein, means on said housing having a sealing engagement in said seat, a gaseous fluid inlet passage from said pressure tube to said housing, upper 45 and lower valve seats in said passage, a control valve in said passage adapted to be moved between said seats, a stem on said valve, an extension sub on said stem, a liquid inlet to said 50 housing, a liquid inlet valve on said sub slidably engaging in said inlet, means to releasably retain said control valve in either of its seats, said control valve being movable from one valve seat to another of said seats by pressure of the gaseous lift fluid to open said liquid inlet valve, said 55 liquid valve being again closed, and said control valve being moved to open position in response to pressure in said housing of the liquid being pumped.

3. The combination of a pressure tube, a flow tube therein, a valve housing on said flow tube, means sealing the lower end of said housing with said pressure tube, a gaseous fluid inlet passage from said pressure tube to said housing, upper 60 and lower valve seats in said passage, a control valve in said passage adapted to be moved between said seats, a stem on said valve, an extension sub on said stem, a liquid inlet to said 65 housing, a liquid inlet valve on said sub slidably 70 engaging in said inlet, said control valve being movable from one valve seat to another of said seats by pressure of the gaseous lift fluid to open said liquid inlet valve, said liquid valve being again closed, and said control valve being moved 75

to open position in response to pressure in said housing of the liquid being pumped.

4. The combination of a pressure tube, a flow tube therein, a valve housing on said flow tube, means sealing the lower end of said housing with said pressure tube, a gaseous fluid inlet passage from said pressure tube to said housing, upper and lower valve seats in said passage, a control valve in said passage adapted to be moved between said seats, a stem on said valve, an extension sub on said stem, a liquid inlet to said housing, a liquid inlet valve on said sub slidably engaging in said inlet, said control valve being movable from one valve seat to another of said seats by pressure of the gaseous lift fluid to open said liquid inlet valve, said liquid valve being again closed, and said control valve being moved to open position in response to pressure in said housing of the liquid being pumped and means to hold said control valve yieldably in its upper seat.

5. In a device of the character described, a flow tube, an intake connection member therein having an inlet passage thereto for gaseous fluid, means to conduct gaseous fluid to said inlet passage, upper and lower valve seats in said passage, a control valve movable between said seats, a stem on said valve, means normally holding said valve resiliently in the upper of said seats, a liquid inlet to said tube, a valve controlling said inlet, means connecting said liquid inlet valve with said control valve, means to releasably latch said control valve in either of said seats, means to move said control valve from the upper seat to said lower seat, and open said liquid inlet valve operating in response to fluid pressure through said passage, said liquid inlet valve being closed and said control valve being opened in response to pressure of the liquid being pumped in said tube.

6. In a device of the character described, a flow tube, an intake connection member therein having an inlet passage thereto for gaseous fluid, means to conduct gaseous fluid to said inlet passage, upper and lower valve seats in said passage, a control valve movable between said seats, a stem on said valve, means normally holding said valve resiliently in the upper of said seats, a liquid inlet to said tube, a valve controlling said inlet, means connecting said liquid inlet valve with said control valve, means to releasably latch said control valve in either of said seats, means to move said control valve from the upper seat to said lower seat and open said liquid inlet valve operating in response to fluid pressure through said passage, said liquid inlet valve being closed and said control valve being opened in response to liquid pressure in said tube, a check valve below said liquid inlet valve,

said check valve being adapted to yield downwardly when said liquid inlet valve is opened.

7. In a device of the character described, a flow tube for wells having an inlet passage for gaseous fluid adjacent the lower end, a liquid inlet below said passage, a control valve in said inlet passage, a stem on said valve, a liquid inlet valve connected with said stem, a packing means in said liquid inlet engaging said inlet valve, said control valve being movable from one closed position to another closed position to open said liquid inlet valve, latching means to hold said control valve in either of said closed positions, and additional means normally holding said control valve resiliently in one of said closed positions, but adapted to yield to allow said control valve to move to open position in response to liquid pressure in said tube.

8. In a device of the character described, a valve rod, a control valve thereon at the upper end of said rod, a liquid inlet valve at the lower end of said rod, upper and lower seats for said control valve, a liquid inlet valve sleeve, packing means in said valve sleeve, said inlet valve being slidable through said packing means, said control valve being movable from one seat to the other to open said liquid inlet valve, and to an intermediate position to close said liquid inlet valve.

9. In a device of the character described, a flow tube, a check valve at the lower end thereof including a valve seat, a valve support slidable over said seat, means to hold said support resiliently upwardly, a valve on said valve seat, a cage for said valve, said valve being adapted to yield downwardly with said sleeve under fluid pressure to allow said valve to move to said seat.

10. In a device of the character described, a flow tube, a standing valve therein including a valve seat, a sleeve surrounding said seat, and a slideable thereon, a valve cage above said sleeve and acting to limit the movement in one direction of said sleeve, a valve on said sleeve and movable therewith by fluid pressure against said seat.

11. In a device of the character described, a flow tube, a standing valve therein including a valve seat, a sleeve surrounding said seat and slideable thereon, a valve cage above said sleeve and acting to limit the movement in one direction of said sleeve, a valve on said sleeve and movable therewith by fluid pressure against said seat, and a transverse plate below said seat having one or more slotted openings to allow passage of fluid to said seat, and to limit or govern the amount of fluid so admitted.

ALEXANDER BOYNTON.
